**Charles G. Kipp and Edward L. Hampton, Louisville,
Ky., assignors to Lear Siegler, Incorporated**

Filed Dec. 23, 1971, Ser. No. 211,819

Term of patent 14 years

U.S. Cl. D6—196

FIG. 1 is a top plan view of a swivel base for supporting a piece of furniture and showing our new design:

FIG. 2 is an elevational view taken substantially along the line 2—2 of FIG. 1; and

FIG. 3 is a top perspective view thereof.

FIG. 3 is a top perspective view thereof.
The design is characterized by the pads on the respective legs of the pedestal base, particularly wherein the pads are channelled on the top and the outward ends and include arcuate bottoms.

We claim:

The ornamental design for a swivel base for supporting a piece of furniture, substantially as shown and described.
